UNITED STATES PATENT OFFICE.

ELTON W. WALBORN, OF CANTON, PENNSYLVANIA.

AUTOMATIC DRAFT-REGULATOR.

1,320,298.

Specification of Letters Patent.

Patented Oct. 28, 1919.

Application filed October 16, 1914. Serial No. 866,966.

To all whom it may concern:

Be it known that I, ELTON W. WALBORN, a citizen of the United States, residing at Canton, in the county of Bradford and State 5 of Pennsylvania, have invented certain new and useful Improvements in Automatic Draft-Regulators; and I do hereby declare the following to be a full, clear, and exact description of the invention, such as will 10 enable others skilled in the art to which it appertains to make and use the same.

This invention relates to automatic draft regulators designed for use in connection with smoke boxes on locomotives and can be 15 used in chimneys or other outlets for furnaces to regulate the draft by admitting the air in the required quantity to insure complete combustion of the fuel, and one of the principal objects of the invention is to provide a device of simple construction which 20 will operate automatically to admit air to the smoke box or smoke stack to regulate the draft, the damper of said regulator being hinged and connected to a spring which 25 can be adjusted to make the damper operate automatically for supplying air.

The foregoing and other objects may be attained by means of the construction illustrated in the accompanying drawing, in 30 which—

Figure 1 is a longitudinal sectional view of the draft regulator, and

Fig. 2 is an end view.

Referring to the drawing by reference numerals, 1 designates a fragmentary portion of a locomotive smoke box. At any suitable point, the smoke box 1 is provided with an opening 1^a to permit of the application of my improved draft regulator.

The draft regulator comprises a comparatively long pipe which consists of an inner section 2 and an outer section 3. These sections are of relatively different diameters, and they are arranged eccentrically to position a portion of the inner section 2 beyond a portion of the outer section 3, the space between the sections being partially closed by a wall 3^a which forms a valve seat. Pivoted at 4 within the section 2 is a damper 5 the diameter of which is smaller than that of the section 2. The damper 5 is held normally closed against the seat 3^a by a spring 6 which is secured at one end to the damper and at its opposite end to a nut 10. The nut 10 is mounted upon a threaded bolt 7 which has threaded engagement with

a bracket 8 carried by the section 3 and which is provided with a manipulating head 9. Through the medium of the nut 10 being turned on the bolt 7 the tension of the spring 6 may be regulated and controlled.

The draft regulator is applied to the smoke box 1 by passing the smaller section 3 through the opening 1^a, and it is secured in position in any suitable manner. To permit a small, but continuous supply of fresh air to the smoke box 1, the valve seat 3^a is indented as at 11 to provide a by-pass between the sections 3 and 2 about the damper 5. This supply of fresh air to the smoke box 70 prevents the creation of an excessive draft through the fire box under ordinary running conditions, such for instance, as when the locomotive is traveling over a level stretch of track. This amount of fresh air 75 entering the smoke box would not prevent the creation of an excessive draft through the fire box when the locomotive is ascending a grade for the reason that during such time the exhaust becomes very heavy. This 80 increase in the exhaust would, however, cause the valve 5 to open and let into the smoke box sufficient air to prevent the increased exhaust from creating through the fire box, a draft that would tend to lift the 85 fire from the grate bars and create holes therein.

It should be apparent from the foregoing description, taken in connection with the accompanying drawing, that I provide a 90 draft regulator which will effectively prevent an increase in the exhaust from creating a draft through the fire box that would lift the fire from the grate bars and create holes therein. It should also be apparent that 95 the device is simple, durable and effective, and that it may be readily and quickly applied to a smoke box at very little cost.

Various changes may be made in the details of construction without departing from 100 the spirit and scope of the invention as defined in the claim.

What is claimed is:

A draft regulator for locomotives comprising an air feed pipe passing through 105 the wall of the smoke box of the locomotive, the inner section of the pipe having a greater diameter than the outer section and arranged eccentrically with relation to the outer section, a wall connecting the projecting part of the inner pipe section to the adjacent part of the outer pipe section and 110

forming a valve seat, a valve pivoted within the larger section, resilient means normally holding the valve seated, said valve seat being indented to provide a by-pass around the 5 valve to permit a continuous, but small supply of fresh air to be fed to the smoke box during ordinary running conditions, and said valve being adapted to be opened on the increase in the exhaust when the train is

ascending a grade to permit a larger quantity of air to enter the smoke box.

In testimony whereof I affix my signature in presence of two witnesses.

ELTON W. WALBORN.
